Primary Examiner — Bridget L Eland(74) *Attorney, Agent, or Firm* — Katherine M. Scholz(57) **CLAIM**

The ornamental design for a communications equipment, as shown and described.

DESCRIPTION

FIG. 1 is a perspective view showing the new design for a communications equipment.

FIG. 2 is a first side view thereof;

FIG. 3 is a second side view thereof;

FIG. 4 is a front side view thereof;

FIG. 5 is a rear side view thereof;

FIG. 6 is a top view thereof; and,

FIG. 7 is a bottom view thereof.

The broken lines in the drawings are for the purpose of illustrating portions of the communications equipment that form no part of the claimed design.
